UNITED STATES PATENT OFFICE.

WILHELM KÖLLE, OF STUTTGART, GERMANY, ASSIGNOR OF ONE-THIRD TO WILLIAM ELWORTHY, OF SUNNYSIDE WELLINGTON, SOMMERSET, ENGLAND, AND ONE-THIRD TO CHRISTIAN HELD, OF STUTTGART, GERMANY.

APPARATUS FOR GENERATING OZONE.

No. 909,309.

Specification of Letters Patent.

Patented Jan. 12, 1909.

Application filed February 12, 1908. Serial No. 415,510.

To all whom it may concern:

Be it known that I, WILHELM KÖLLE, a subject of the King of Great Britain, and resident of 55 Neue Weinsteige, Stuttgart, in the Kingdom of Würtemberg, Germany, have invented certain new and useful Improvements in Apparatus for Generating Ozone, of which the following is an exact specification.

10 This invention relates to improvements in apparatus for generating ozone as described in Patent No. 653,078 granted to Elworthy and dated July 3rd, 1900. In this patent there is described a construction of apparatus 15 in which several ozonizing elements are enclosed in a casing. These ozonizing elements consist of dielectric tubes having inner and outer conductors said conductors being out of contact with the dielectric tubes. In this 20 way electric discharges take place between the conductors and the adjacent walls of the dielectric and the air is ozonized by passing first through the interior of the dielectric tube and then over the exterior. 25 According to the present invention the air instead of passing through the tube and then coming in contact with the exterior walls thereof is passed through a plurality of concentrically arranged tubes with coils sup- 30 ported at a short distance from the walls thereof so that the outer coil on one tube forms the inner conductor for the dielectric tube of next largest diameter surrounding the first mentioned tube. 35 The nature of the present invention and the manner in which it is carried into effect will be more readily understood from the following description of the apparatus represented in the accompanying drawing, which 40 shows a cross section through an element of an ozonizing apparatus.

According to the form of this invention illustrated a central dielectric tube *a* is surrounded by two other dielectric tubes *b* and *c*, these dielectric tubes being composed of a material able to withstand a very high potential difference on either side thereof. Through the central tube *a* there passes a rod *d* which however does not touch the walls thereof. 45 The tube *a*, the rod *d* and the tube *b* are all supported in an insulating cap *i* which may be screwed or otherwise fixed to a partition *m* in the box *p*. Round the exterior of the tube *a* there is wound a coil *f* which is kept by

any suitable means at a short distance from 55 the outer wall of the tube. Round the exterior of the tubes *b* and *c* similar coils *g* and *h* are wound. The lower end of the tubes *a*, *b* and *c* fit into a double cover or cap *l* which is fixed to both partitions *n* and *o* of the casing 60 *p*. The coils *h* and *f* are connected to a terminal *q*. In this way there is formed a series of concentric coils, alternate coils of which are connected to one terminal while the other set of alternate coils are connected to the 65 other terminal.

The operation of this device is as follows:—Air enters the central chamber of the casing *p* by means of a pipe *s* as shown by the arrow. This air then passes through openings in a cap *k* at the end of the outer pipe *c* and through the annular space left between the outer dielectric tube *c* and the first inner dielectric tube *b*. As the coil *h* is connected to the terminal *r* while the coil *g* is connected to the terminal *q* electric discharges pass between the coil *h* on the wall of the dielectric and also between the coil *g* and the inner wall of the dielectric tube *c*. The air passing from the pipe *s* is therefore ozonized to some 70 extent by the discharges external to the dielectric tube *c* and then is further ozonized by the internal discharges taking place between the coil *g* and the inner surface of the tube *c*. As however the coil *f* is connected to the terminal *a* and the coil *g* is connected to the terminal *q* a similar action to that above described takes place between the coil *g* and the external wall of the tube *b* and between the coil *f* and the internal wall of the dielectric tube *b*. A similar action also takes place with regard to the walls of the inner dielectric tube *a*. It will be seen therefore, that each coil conductor acts as the inner conductor for the tube outside it and as an 75 outer conductor for the tube which it surrounds. There is therefore obtained by an arrangement of concentric dielectric tubes and coils in the manner described a great saving in the current while the ozonizing 80 effect is increased.

It will be understood that the air after passing through the annular space between the tube *c* and the tube *b* passes up through the annular space between the tube *b* and the tube *a* and then passes downward through the central tube *a* as shown by the arrows. The arrangement may as easily seen, be ex- 85 90 95 100 105

panded to include a greater number of concentrically arranged dielectric tubes.

Having thus fully described the nature of my invention, what I desire to secure by Letters Patent of the United States is:—

Apparatus for generating ozone, comprising a casing to which air to be ozonized is led, ozonizing elements in said casing and comprising a plurality of concentrically arranged dielectric tubes, conductors between said tubes, a conductor on the outer tube, a conductor within the inner tube, said conductors being out of contact with the dielectric

tubes and each conductor being connected to the opposite pole of a source of current to the conductor lying radially within it, divisions in said casing forming chambers which are connected in series through the concentrically arranged dielectric tubes of the ozonizing elements, substantially as described.

In witness whereof I have hereunto set my hand in the presence of two witnesses.

WILHELM KÖLLE.
